(57) **CLAIM**

The ornamental design for an electric computer, thereof as shown and described.

DESCRIPTION

FIG. 1 is a front perspective view of an electronic computer, showing our new design, showing the display in an open position and the arm in an extended position;

FIG. 2 is a front perspective view thereof showing the display in an open position and the arm in a retracted position;

FIG. 3 is a front perspective view thereof showing the display in a closed position and the arm in a retracted position;

FIG. 4 is a front perspective view thereof showing the display in a forward open position and the arm in an extended position;

FIG. 5 is a front elevational view thereof showing the display in an open position and the arm in an extended position;

FIG. 6 is a rear elevational view thereof showing the display in an open position and the arm in an extended position;

FIG. 7 is a left side view thereof showing the display in an open position and the arm in an extended position;

FIG. 8 is a right side view thereof showing the display in an open position and the arm in an extended position;

FIG. 9 is a top plan view thereof showing the display in an open position and the arm in an extended position;

FIG. 10 is a bottom plan view thereof showing the display in an open position and the arm in an extended position;

FIG. 11 is a rear perspective view thereof showing the display in an open position and the arm in an extended position;

FIG. 12 is a rear perspective view thereof showing the display in a rotated open position and the arm in an extended position; and,

FIG. 13 is a rear perspective view thereof showing the display in a forward open position and the arm in an extended position.

The broken line showing of the remainder of the electronic computer is for illustrative purposes only and forms no part of the claimed design.
